FRITZ HESS, OF HAGEN, WESTPHALIA, GERMANY

PROCESS AND APPARATUS FOR MANUFACTURING ANATOMICALLY ACCURATE
INDIVIDUAL FOOT SUPPORTS FOR SHOES

Application filed February 15, 1929, Serial No. 340,298, and in Germany March 7, 1928.

The manufacture of anatomically accurately fitting supports for abnormal feet requires a great deal of work and care and considerable working skill. The last is made as a rule of plastic quick hardening material such as gypsum or the like. As a rule the metallic supports are formed according to the negatives thus obtained by hammering or bending by hand. Errors happen often in such insoles.

The present invention does not utilize these known methods and media. According to the invention the negative is formed by thin spring-controlled metallic pins suitably arranged in a box closely juxtaposed, which together in their unloaded position form an absolutely flat surface. The patient stands with the necessary weight on the surface formed by the pins. These pins, each of which moves individually and independently of the others, conform exactly with the shape of the foot. The pins are then held in the box in their depressed position by clamping or pressing means. A second positive impression is obtained by inverting a second box containing loose pins over the box containing the negative impression of the foot, which loose pins conform exactly with the negative form. The positive and negative thus obtained form a kind of die or stamping form between which the metal plates for the support are shaped by pressing. The only subsequent work required is smoothing off along the edges.

An embodiment of the invention is illustrated by way of example in the accompanying drawings, in which

Fig. 1 shows a perspective view of the apparatus.

Fig. 2 is a part sectional view of the apparatus on larger scale.

Figs. 3 and 4 show each a portion cut out of an element in top plan view on considerably larger scale.

In a suitable rectangular metal box *a* which is somewhat longer and wider than the largest foot coming into question, pins *b* of square cross section are arranged vertically closely juxtaposed in longitudinal and transverse rows, said pins forming together a complete surface. Each pin *b* has an extension *c* at one

end mounted in a corresponding hole of plate *d* loosely inserted in the box *a*. The plate *d* is fixed in the box at a certain distance from the bottom of the box so that the pins can adjust themselves in vertical direction, as shown in Fig. 2. A nut *f* screwed on the threaded rear end of the pin *b* prevents the pin from falling out of plate *d*. Springs *e* wound around the extensions *c* of the pins *b* rest at one end against the perforated plate *d* and at the other end against the lower surface of the corresponding pin *b* and to maintain said pins in their raised position. Each individual pin *b* can be adjusted freely and independently from its companion pins, as shown in Fig. 2. The box *a* is mounted between guide bars *g* of a frame and adapted to be pulled out on one side of the frame.

In order to obtain a negative mould of the foot of a patient, this patient has to put his foot on the surface formed by the pins *b*. The pins *d* sink to different depths according to the shape of the foot and form a bed conforming in every detail with the anatomical structure of the foot.

A locking bar *i* is inserted into slots *h* in the front ends of the side walls of box *a* in which it bears against the pins *b*. This locking bar *i* is secured in its locking position by eccentric discs *m* rotatably mounted in bearings *k* and each provided with a handle *l*. By oscillating the handles *l* in the direction of the arrow, the eccentric discs *m* press against the bar *i* which will be forced into the box *a*. Owing to the great frictional pressure thus produced, not only all the pins which were hitherto freely movable, as shown in somewhat exaggerated form in Fig. 4, are clamped securely, in position, as shown in Fig. 3, and also are pressed so tightly against each other that they cannot alter their position even under comparatively strong pressure.

In a frame *o* a second box *p* containing pins *q* is arranged. This box *p* is provided with an exactly similar arrangement also with similar clamping arrangement as box *a*, only the springs *e* are omitted, so that the pins *q* can move freely in the carrying plate. First all the pins *q* are secured in their raised

position by means of a clamping bar *i*. This position can be attained by simply lowering the box *p* onto the flat surface of the box *a*. After the negative form with the box *a* has been pushed under the box *p* the clamping device in this latter box is released. The pins *q* will then drop loosely onto the negative moulds in the box *a*, so that a positive mould is produced. The pins *q* are then secured in their adjusted position by the clamping device.

The box *p* is again raised and a thin metal plate *r*, generally of aluminium is introduced between the two moulds, whereupon by screwing down the spindle *s* said plate will be pressed to the proper shape. The metal plate or support when removed from the moulds is finished and only requires smoothing along the edges.

20 I claim:—

1. A method of manufacturing supports for flat feet from the natural foot consisting in producing a negative mould corresponding exactly to the actual shape of the sole of a foot by pressing said foot onto a yielding surface composed of a plurality of juxtaposed elements, in mechanically fixing this mould in its position, in producing a positive mould from said negative mould by pressing a similarly composed yielding surface on to said negative mould, in mechanically fixing said positive mould, and in stamping a metal plate between said positive and negative moulds to form a support corresponding accurately to the shape of the foot of the wearer.

2. An apparatus comprising in combination a lower mould, composed of a number of spring-controlled, vertically displaceable, closely juxtaposed pins forming together a yielding surface, means for locking said pins in any vertical position, an upper mould adapted to be placed on said lower mould and composed of a number of freely vertically displaceable closely juxtaposed pins forming together a mouldable surface, means for locking said pins in any vertical position, and means for pressing said upper mould with an interposed plate of sheet metal on said lower mould.

In testimony whereof I affix my signature.
DR. FRITZ HESS.
